Primary Examiner — Lauren R Calve(74) *Attorney, Agent, or Firm* — Patents and Licensing LLC; Daniel W. Juffernbruch(57) **CLAIM**

The ornamental design for a diamond-shaped handle for tool, as shown and described.

DESCRIPTION

FIG. 1 is a front perspective view of a diamond-shaped handle for tool shown in environmental use;

FIG. 2 is a top perspective view of the diamond-shaped handle for tool shown in partial environmental use;

FIG. 3 is a bottom perspective view thereof;

FIG. 4 is a front view thereof;

FIG. 5 is a rear view thereof;

FIG. 6 is a first side view thereof;

FIG. 7 is a second side view thereof;

FIG. 8 is a top view thereof; and,

FIG. 9 is a bottom view thereof.

The broken lines shown are for illustrative purposes only and form no part of the claimed design.
